UNITED STATES PATENT OFFICE.

JAMES W. HUBBER, OF SAN FRANCISCO, CALIFORNIA, ASSIGNOR OF ONE-HALF TO ABRAM ALTMAYER, OF SAME PLACE.

SMOKE-CONSUMING FURNACE.

SPECIFICATION forming part of Letters Patent No. 365,342, dated June 21, 1887.

Application filed August 21, 1885. Serial No. 175,018. (No model.)

To all whom it may concern:

Be it known that I, JAMES W. HUBBER, a citizen of the United States, residing at San Francisco, in the county of San Francisco and State of California, have invented certain new and useful Improvements in Smoke-Consuming Furnaces, of which the following is a specification.

My present invention relates to certain new and useful improvements in that class of smoke-consuming furnaces for which Letters Patent of the United States were granted to me on December 16, 1884; and my invention consists in forming a chamber back of the bridge-wall of the furnace, over which a perforated plate is placed. Atmospheric air is led into the chamber, which passes up through the perforated plate and meets the flame from the furnace at the top of the bridge-wall.

It also relates to a cowl or hood of peculiar construction placed in the smoke-stack or chimney of the furnace, and to the other details of construction and operation, to be hereinafter fully described.

In the accompanying drawings, forming a part of this specification, Figure 1 is an elevation of my smoke-consuming furnace, with part of smoke-stack broken away to show the cowl or hood. Fig. 2 is a cross-section through the combustion-chamber of the furnace. Fig. 3 is a cross-section through the cold-air chamber. Fig. 4 represents a section and elevation of hood or cowl.

Similar letters refer to similar parts throughout the several views.

In place of the air or smoke passages at the end of the exhaust-pipe, which enters the smoke-stack, as set forth and described in my Letters Patent of December 16, 1884, I employ a cowl or hood, A, provided with slotted passages or openings A', and around the hood or cowl is placed a casing or register, B, having like openings, as shown at A', and this casing is arranged so as to be moved to the right or left by means of eye-holes C, to which small chains C' are connected, passing down in front of the stack or chimney, to wholly or partially exclude the passage of smoke or exhaust steam from the furnace. Through the cowl or hood a space is left, however, of three or four inches between its greatest diameter and the

stack. This hood connects with the exhaust-fan D through the medium of the pipe E, and intermediate between the stack and exhaust-fan is placed a valve, F, and a damper, G. 55 The purpose of the former is to admit atmospheric air to the exhaust-fan, and the office of the latter is to shut off communication with the smoke-stack.

A pipe, H, is connected to the outer end of 60 the exhaust-fan chamber and passes down into the furnace beneath the grate-bars and receives all of the products of combustion drawn from the smoke-stack by the suction-fan, as described in my former Letters Patent of December 16, 1884. From the pipe H extends a branch pipe, I, provided with a suitable cock, I', which connects with a suction and forcing fan, J, located upon the wall of the furnace, to be hereinafter more fully described.

Back of the bridge-wall of my furnace I construct a cold-air chamber, K, the top of which is open, and over the opening I place a perforated plate, L, which rests upon the walls of the chamber, slightly inclining upward or 75 backward from the front wall to the back or rear wall thereof.

The front edge of the perforated plate is raised a little above the top of the front wall of the chamber, so that a small space, M, is 80 left between the lower face of the plate and the upper face of the wall, whereby a thin sheet of atmospheric air is forced out of the chamber at its point to meet the opposing flame from the furnace.

To the branch pipe I is connected a vertical pipe, N, provided with a damper or valve, O, which enters the cold-air chamber K, passing through the wall thereof. These pipes are so arranged that atmospheric air from the suction and forcing fan can be conducted into the pipe H and supply a greater amount of oxygen to the furnace beneath the grate-bars by opening the valve I'. 85

Both the suction and forcing fans are driven 95 by steam from the boiler through the medium of a belt-connection passing around pulleys at one side of the casings of the respective fans.

In operation, the casing around the cowl or hood is opened and the damper in the exhaust-pipe closed, so as to give free draft to the smoke-stack until the fire in the furnace has made suffi-

cient headway, when the casing or register around the hood is operated by the small chains so as to close the openings in the hood, and the damper G is opened and the fans set in motion, which draws the products of combustion from the smoke-stack or chimney into the exhaust-fan D and forces it down into the furnace beneath the grate-bars. At the same time, the damper or cock I being closed, atmospheric air will be drawn into the fan-chamber and forced down into the cold-air chamber through the medium of the vertical pipe N and up through the perforations in the plate L and the small space between the edge of the plate and the top of the wall, the former in jets and the latter in a thin sheet, which meets the incoming or opposing flame, which consumes all the unconsumed products of combustion drawn from the smoke-stack, together with the direct unconsumed products of combustion from the fuel in the furnace which have not escaped into the smoke-stack, in so complete and full a manner that nothing but a thin unclouded vapor will be seen issuing from the top of the chimney or smoke-stack of the furnace to which my invention is applied.

When the thin volume of atmospheric air which is forced from the cold-air chamber through the small slot or opening between the plate and bridge-wall of the furnace above described meets the opposing flame from the fuel-chamber or furnace, a sheet of blue flame will constantly be seen above the bridge-wall, thereby consuming all products of combustion capable of being consumed.

Should a greater volume of oxygen be required, the cock or damper I' in the cold-air pipe I may be opened and admit atmospheric air to the pipe H to mingle with the smoke taken from the smoke-stack, which is forced into the chamber beneath the fire-grate of the furnace, as above described. It should here be observed that in order to avoid the shrinking and warping of a metal plate for the cold-air chamber a plate composed of fire-proof tiling or bricks may be employed, having suitable holes or openings through them for air-passages.

Having thus described my invention, what I claim, and desire to secure by Letters Patent, is—

1. In a smoke-consuming furnace, the exhaust-pipe of the smoke-stack or chimney provided with a hood or cowl with suitable openings, and a casing or register with like openings operated by suitable chain or other connections for regulating the draft in the said stack and conducting the unconsumed products of combustion from the furnace into the exhaust-pipe, as described.

2. In a smoke-consuming furnace or engine,

the suction and forcing fan or blower J, which connects with the pipe H and the cold-air pipe N to conduct atmospheric air into the furnace beneath the grate-bars or to the cold-air chamber to the rear of the bridge-wall, as described, for the purpose set forth and specified.

3. In a smoke-consuming furnace, providing a small space between the top of the bridge-wall and the perforated plate, so that a thin sheet of atmospheric air will be forced out of the cold-air chamber at that point and meet the incoming or opposing sheet or volume of flame from the furnace, as described, for the purpose specified.

4. In a smoke-consuming furnace in which a suction blower or fan is employed to draw the products of combustion from the stack, an inverted-funnel-shaped mouth-piece provided with ports or apertures controlled by valves or gates, said mouth-piece being located in the stack of the furnace and connected with the blower, substantially as herein described.

5. In a smoke-consuming furnace, the inverted-funnel-shaped mouth-piece A in the stack, provided with ports or apertures controlled by valves or gates, said mouth-piece being connected with a suction blower or fan, substantially as herein described.

6. In a smoke consuming furnace, the inverted-funnel-shaped mouth-piece A in the stack, having ports or apertures controlled by valves or gates, in combination with the pipe E, connecting-elbow, suction-blower D, and pipe H, substantially as herein described.

7. In a smoke consuming furnace in which a suction blower or fan is employed to draw the products of combustion from the stack, the inverted-funnel-shaped mouth-piece A, located in the stack, and having a diameter at its base but little less than the diameter of the stack, said mouth-piece being connected with the blower, and provided with ports or apertures controlled by valves or gates, substantially as and for the purpose herein described.

8. In a smoke-consuming furnace, the suction-blower D, pipes H and E, and an elbow entering the stack, in combination with the inverted-funnel-shaped mouth-piece G in the stack and joined to the elbow, said mouth-piece having ports or apertures A', and the valve or gate B, by which the ports are opened or closed, substantially as herein described.

In testimony that I claim the foregoing I have hereunto set my hand and seal.

JAMES W. HUBBER. [L. S.]
